(57) **CLAIM**

The ornamental design for earphones as shown and described.

DESCRIPTION

FIG. 1 is a perspective view of earphones showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1; and,

FIG. 12 is an enlarged view of portion 12 shown in FIG. 2.

The earphones are shown with symbolic breaks in the lengths of the earphone cables; the dot-dash broken lines thereof and the appearance of any portion of the earphones between the break lines form no part of the claimed design. The dash-dash broken lines in the drawings depict portions of the earphones that form no part of the claimed design. The dot-dash broken lines in FIGS. 1-2, and 9-12 represent boundaries of the enlarged portions and form no part of the claimed design.
